CLAIM

We claim the ornamental design for a case for mobile phone, as shown and described.

DESCRIPTION

FIG. 1 is a front, left and bottom perspective view of a case for mobile phone showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlarged view of an encircled portion 9 of FIG. 2.

The broken line circles in FIGS. 2 and 9 are provided for the purpose of indicating the portion included in the partial enlarged view and form no part of the claimed design.

1 Claim, 9 Drawing Sheets
